UNITED STATES PATENT OFFICE.

GEORGE WEBSTER HOUSTON, OF SAVOY, ASSIGNOR OF ONE-HALF TO
S. LA FAYETTE EASLEY, OF FORT WORTH, TEXAS.

SPRING-MOTOR FOR FANS.

SPECIFICATION forming part of Letters Patent No. 390,369, dated October 2, 1888.

Application filed March 12, 1888. Serial No. 266,982. (No model.)

To all whom it may concern:

Be it known that I, GEORGE WEBSTER HOU-
TON, a citizen of the United States, residing at
Savoy, in the county of Fannin and State of
Texas, have invented certain new and useful
Improvements in Spring-Motors for Fans; and
I do hereby declare the following to be a full,
clear, and exact description of the invention,
such as will enable others skilled in the art
to which it appertains to make and use the
same.

This invention relates to a device for oper-
ating a fan or other object to which it is desir-
able to give a continuous reciprocating mo-
tion; and it consists in the novel construction
and combination of the parts, hereinafter fully
described and claimed.

In the drawings, Figure 1 is a side view of
the complete device. Fig. 2 is a rear view of
the lower portion of the same. Fig. 3 is also
a rear view of the motor, drawn to a larger
scale.

Portions of the casing are shown broken
away in all the views to display the mechanism
within.

A is the casing, which incloses the spring and
toothed wheels, and B is a stand provided with
wheels b, so that the whole apparatus may be
moved about to different parts of a room with
facility.

C is an upright secured to the case A and
provided with the long slot c.

D are side pieces, and d are thumb-screws,
which pass through them and through the
slot c, so that the height of the fan can easily
be regulated.

E is the top piece, secured to the side pieces,
D, and e are inclined braces, which also sup-
port the top piece.

F is the fan, and f is the fan-lever, pivotally
connected at its top end to the top piece, E.

G is a revolving shaft provided with the
crank g and journaled in the case A.

H is a bell-crank lever, provided with a
weight, h, for balancing the crank and con-
necting-rod.

I is the connecting-rod for the crank, pro-
vided with the joint i, so that its length may
be varied to suit the height of the fan, and J
is a rod which connects the fan-lever with the
top arm of the bell-crank lever.

The shaft G is revolved by means of the
spring K, secured upon shaft k, which is also
journaled in the case A.

L are intermediate toothed wheels, which 55
communicate the motion of shaft k to shaft G,
and which are so proportioned as to give mo-
tion to the fan.

M is the fly-wheel, secured upon the shaft G.

N is a brake pivoted on the pin n, which 60
projects from the case A, and bearing against
the said fly-wheel.

O are hooks upon the brake, and P is a
spring, one end of which is secured to one of
the said hooks. This spring is formed of india- 65
rubber cord; but springs of other material—
as, for instance, a helical wire coil—may also
be used. The other end of the spring P is
wound upon the shaft k by the action of wind-
ing up the mainspring K.

R are small pulleys over which the spring P
passes, and which are supported by the case
A at suitable points for the guidance of the
said spring.

The spring K has its outer end secured to 75
the casing by the bracket m, and its inner end
is secured to the shaft k. A square portion,
k', is formed upon the end of shaft k for the
winding-up handle. h is a ratchet on shaft k,
and h' is a pawl which prevents the spring 80
from unwinding when not required, the said
pawl being pivoted to the case and engaging
with the ratchet, as in ordinary clock-work-
winding mechanism.

The intermediate gearing, L, may be variously proportioned and va- 85
ried to adapt it to the size and strength of the
mainspring employed, and upon which the
length of time for which the motor will run
will necessarily also depend. The gearing L
(shown in the drawings) consists of a wheel, l, 90
secured on the spring-shaft and gearing into a
pinion, 2, on shaft 3 behind the spring-shaft.
A wheel, 4, is also secured on shaft 3 and gears
into a pinion, 5, upon shaft 6. A wheel, 7, is
also secured upon shaft 6 and gears into the 95
pinion 8, which is secured upon the crank-
shaft.

When the mainspring is fully wound up, the
spring P causes the brake to bear hard against
the fly-wheel and the motion of the fan is re- 100
tarded, the exact adjustment of speed being
regulated by attaching the end of spring P

to whichever hook O permits the best result to be obtained. As the mainspring runs down the spring P is unwound, so that the brake does not bear so hard against the fly-wheel, and the fan 5 therefore operates with a substantially uniform motion all the time it is in operation.

It is obvious that the motion of the lever f might be used to rock a cradle or operate any 10 light mechanism which required a substantially-uniform reciprocating motion. I do not therefore confine myself to the use of the above-described mechanism in connection with a fan.

What I claim is—
15 1. The combination of the continuously-revolving crank-shaft, the fly-wheel on the crank-shaft, the mainspring, the revolving shaft connected to the mainspring, intermediate toothed wheels connecting the spring-shaft with the 20 crank-shaft, the pivoted brake pressing on the fly-wheel, and a spring connected to the said

brake and wound upon the said mainspring-shaft, whereby the crank-shaft may receive a substantially-uniform motion.

2. The combination of the revolving crank-shaft, the fly-wheel secured thereupon, the mainspring, the mainspring-shaft, intermediate toothed wheels connecting said shafts, the pivoted brake pressing on the fly-wheel, a series of hooks on the brake for the attachment of the compensating spring, the guide-pulleys, and the compensating spring of india-rubber cord passing over the said pulleys and wound upon the mainspring-shaft, so that the crank-shaft may have a substantially-uniform 35 motion.

In testimony whereof I affix my signature in presence of two witnesses.

GEORGE WEBSTER HOUSTON.

Witnesses:

JAMES A. MASON,
JOHN DEATHERAGE.
